UNITED STATES PATENT OFFICE.

FREDERICK G. SARGENT, OF WESTFORD, MASSACHUSETTS.

APPARATUS FOR SELECTIVE WIRELESS TELEGRAPHING.

1,102,442.

Specification of Letters Patent.

Patented July 7, 1914.

Application filed November 21, 1913. Serial No. 802,189.

To all whom it may concern:

Be it known that I, FREDERICK G. SARGENT, a citizen of the United States, residing at Westford, in the county of Middlesex 5 and State of Massachusetts, have invented a new and useful Apparatus for Selective Wireless Telegraphing, of which the following is a specification.

This invention relates to a system of communicating or telegraphing, and for other purposes, particularly adapted for use with wireless apparatus.

The principal objects of the invention are to secure secrecy and simplify both the sending and receiving operations.

The invention also involves improvements in features of construction and combinations of parts as will appear hereinafter.

Reference is to be had to the accompanying drawings in which—

Figure 1 is a diagrammatic elevation of a sending station. Fig. 2 is a similar view of a receiving station adapted to coöperate therewith. Fig. 3 is a side elevation showing the details of one of the keys of the sending station. Fig. 4 is a similar view showing another position of the parts. Fig. 5 is a plan of a sending dial of modified form. Fig. 6 is a similar view of another form of a receiving dial with a diagrammatic illustration of connections therewith for operating a typewriter. Fig. 7 is a similar view showing an automatic arrangement for operating the typewriter. Fig. 8 is a 5 view of one of the dials showing a modification, and Fig. 9 is a similar view showing another modification.

Referring to Figs. 1 and 2 it will be seen that at each station there are two members 40 one rotary and one stationary, namely a dial 10 and a pointer or indicator 11. For the purpose of this invention either the dial or the pointer may rotate and in the form shown in Figs. 1 and 2 the dial is intended 45 to be stationary and the indicator to rotate. The means for rotating the rotatable member is not shown herein but any well known form of clock work or other rotating mechanism can be employed. It is intended to 50 have the rotation at the several stations synchronous. For this purpose the instruments can be set or adjusted by the time signals sent out by the wireless stations every day or they can be provided with extremely 55 accurate instruments so they will keep correct time with each other. At any rate,

when commencing to operate, the stations can be adjusted to see if they are in unison by any simple means.

With the parts arranged as so far described, the apparatus can be used with any ordinary sending and receiving system, either wireless or otherwise.

This mode of operation is as follows:—The station wishing to talk calls the other station or stations in any usual way. After receiving the answer they can, if necessary, compare their dials to see that they are in unison and if not, adjust them so that they will be. The several dials, being provided with series of characters arranged in the same order thereon and rotating in the same direction, or the indicator rotating in the same direction as the case may be, the operators at the stations can give a pre-arranged signal, as for example “a” and if the signal is received at the stations when the indicators and dials are at that point it will be understood that all the instruments are in unison. The sending operator then sends signals by giving any predetermined signal, as a dash or dot, over the apparatus when the indicator 11 indicates the desired letter or character on his dial. The instruments being in unison and the signal being sent instantaneously the receiving station will get the signal when its indicator is showing the same letter or character. It will be understood, of course, that ordinarily the same signal will be sent over the wireless apparatus each time so that to any station not having this apparatus the communications from the sending station would appear to be a repetition of the same signal but at unequal intervals.

This system can be used also in actual connection with the wireless apparatus now in use and for this purpose the following connections are shown. On each of the dials 10 there are a series of contacting pins 12 corresponding in number with the characters on the dials, and the indicator 11 contacts with these periodically as it rotates. In Figs. 1 and 2 the indicator is shown as having a projection 13 for this purpose and the pin with which this projection is shown in contact in Fig. 1 would represent the character A or 1. From each of these pins 12 a conductor 14 is taken off which is connected with a push button 15 having a character thereon corresponding with the character which the indicator shows when that pin 12 is in contact with

it. These push buttons 15 thus constitute a key board. Each one is provided with a contact 16 which engages a bar 17 when the key is operated. This bar is connected with an electro-magnet 18 connected with a battery 19. This in turn is connected with the metallic case 20 in which the dial is located, which is electrically connected with the shaft 21 with which the metallic indicator 11 rotates. Consequently as the indicator rotates it periodically closes each of the several circuits one at a time, no two ever being closed at the same time. The operation of any one of the keys 15 of the key board closes that circuit at one point and then the circuit is completed whenever the indicator gets around to the position which indicates the same character. Then the magnet 18 is energized, a contact 22 is made, and a current is set up in the usual primary 23 and secondary 24. The circuit in which the secondary circuit 24 is located is provided with the usual condenser 25, oscillators 26, aerial 27, and tuning coil 25^a.

The receiving station is shown of a well known type having the aerial 28, coil 29, condenser 30, and detector 31. It is also provided with a telephone receiver 32 and this circuit is connected up with the dial at this station in a manner similar to that described at the other station, but there is no key board. One end of the circuit is connected with the case of the dial so that it is constantly connected with the indicator and the other end of the circuit is divided into as many lines as there are characters and one connected with each of the pins 12.

It will be understood of course that while I have described a complete sending station and a complete receiving station separate from each other, ordinarily each station will actually be provided with both the receiving and the sending mechanism. In this case the sending station is connected up for receiving purposes by simply switching out the battery 19 and connecting these wires to a telephone circuit located at what I have called the sending station. In either case the telephone circuit is closed only when the dial and indicator are in the same relative position as that in which they are in at the sending station. At other times nothing can be heard on the telephone receiver as its connections are broken. It will be understood, of course, also that the telephone receiver can be dispensed with and a receiver used in the ordinary way for operating the relay. The relay then can operate lights or other apparatus for signals or other desired kind of communication or purposes. It will be understood, of course, also that the clock mechanism for operating the dials or indicator can be made to run only for a definite period of time

if desired before requiring rewinding, or that the same can be made on the same principle as a stop watch so that it can be stopped and started as desired to save some of the rewinding. With a stop watch arrangement it can be arranged to start always on a definite character and then the device can be employed to place the several stations in unison. It will be understood, of course, that the clock work can be regulated so that the hand or dial can be made to revolve at any convenient speed, depending upon the size thereof and the distance apart of the characters.

In connection with Figs. 1 and 2, I have referred to the connection of the contacts of the branch circuits 14 by the operating push buttons as being accomplished by contacts 16 engaging a bar 17. This will result in the sending of a simple signal equivalent to a dot or dash of the telegraphic code. I prefer, however, to send a more distinctive signal each time and preferably the same one by each push button so that to a person not having at hand a receiving dial, the signals received would appear to be all alike but at varying intervals apart. For this purpose the construction shown in Figs. 3 and 4 is a convenient one. In this case each push button 15 is mounted on a rod 41 vertically reciprocating on a bracket 42. On a stationary conducting bar 43 insulated from the brackets 42, are the spring contacting bars 17 which are insulated on the top. This bar 43 is connected with the wire which goes to the electro-magnet 18. On the rod 41 are a series of teeth 16^a and the contact 16. The teeth 16^a are narrow and the contact 16 is long. The former represent dots and the latter a dash in the telegraphic code. It will be obvious of course that any desired combination of dots and dashes can be used. In the present case it is intended to give a signal corresponding to four dots and a dash. On the back of the rod 41 is a tooth 44. A latch 45 is pivoted over it and located in a position to engage it. An electromagnet 46 is mounted in a shunt in each of the circuits 14 so that when that shunt is closed the latch 45 will be drawn toward the magnet out of the path of the projection 44.

The operation of the device is as follows: When the operator desires to send a signal, he presses down the button 15 corresponding to that signal. The latch 45 acting by gravity, in the form shown, latches that button down. It will stay down until the corresponding shunt circuit 14 is closed at the dial and then the latch 45 will be drawn away to release the rod 41. This permits a spring 47 to raise the bar. As it raises it the contact is made at 17, through the electromagnet 18 and that signal is sent through the aerial 27. It will be under-

stood of course that as the dial or pointer rotates, each of the magnets 46 will be energized in turn, but this will have no effect except to draw the latches 45 idly to the 5 magnets and then release them, because the other push buttons are in elevated position. It will also be understood, of course, that when pressing down the push button no signal is sent. This is because of the insulation 10 on the top of each contact 17. Moreover, as magnet 18 is connected up in series with each of the circuits 14 there could be no signal unless one of these circuits 14 was closed by the indicator and that one must 15 be the one connected with the push button which was being depressed in order to send a signal even if this insulation were not present.

A similar result can be obtained by the 20 construction shown in Fig. 5. In this case the indicator is a light spring 48 and adjacent to each letter on the dial 49 which rotates in this case, is a contact piece 50 having short and long notches arranged as desired. 25 In the case of Figs. 3 and 4 I have described the notches as arranged exactly the same for every push button. In this case, however, a different arrangement of dots and dashes can be employed and I have shown it so 30 in Fig. 5. These can be arranged according to the Morse code, of course, or in any other desired way. In this case the conducting casing 51, from which the spring 48 is insulated, is electrically connected with the 35 rotating dial and also with the battery 19^a and an ordinary push button 15^a. The receiving circuit in this case may be connected if desired to an ordinary Morse tape machine, not shown. In this case, now assuming 40 the construction in Fig. 5 to act as a receiving station, it will be seen that when a signal is received, the operator presses the push button 15^a to complete the circuit of the battery and dial with the Morse tape machine. Thus the selector will then print the 45 dots and dashes which are controlled by the receiving dial and not by the sending dial.

In the form shown in Fig. 6, which is a receiving station, a typewriter is indicated 50 having keys 52 each one designed to be operated by an electromagnet 53. Each of these electromagnets is in a circuit connected at one end to the casing of the dial and at the other connected to a spring 54. There 55 is one of these springs for each letter and on the rotating dial is an indicator 55 which engages these springs in turn as the dial rotates. Thus each of the circuits is closed at this point in turn. Now when a signal is received, the operator presses down on the key 15^b and completes the circuit through the electromagnet 53, which is in the branch circuit that is being closed by the indicator when this key of the typewriter is depressed. 60

65 The typewriter is arranged to print on a

strip of paper or ribbon and the result is similar to that taking place in the construction shown in Fig. 5 when using the Morse tape machine.

Instead of using the key 15^b in Fig. 6, the 70 device can be made self-operative by using a detector 57 connected up as shown in Fig. 7, with the aerial 28, condensers 30, electromagnets 53, and springs 54.

In Fig. 8 another construction is shown in 75 which the dial 35 rotates and is provided with a cover 36 having openings 37 therethrough constituting an indicator so that it will be simpler for the operator to tell which character is in the position for communication. The keys and contacts are used 80 as in Fig. 1.

In Fig. 9 another arrangement is shown in which there is a relative rotation between the dial 38 and the cover 39, a space 40 being 85 provided for the purpose of designating the position of the letter called. This is merely an indicator without electrical connections.

In the use of this device each party has one of the instruments and by means of a 90 wireless signal system of any desired character or kind, they can determine when the two devices are operating in synchronism. For example it can be understood that the sending station will send out a signal when 95 the letter "A" is behind the space 40 and then the other stations will adjust their devices to be at the same point. Then the station giving the signals can signal the other station or stations whenever any desired letter or number is in the space 40. The receiving stations will, of course, know that 100 fact and thus understand the message.

It will be understood of course that this principle can be used with instruments for 105 giving an audible signal instead of a visual one or in addition to it. For example, where a Morse recorder is used the signals can be given by a sounder, or the like.

Whether connected up as described or used 110 simply as a selective signaling device without the electrical connections, it is obvious, that such an arrangement will prevent the reading of the messages by any party not having such a device and yet the operations 115 of receiving and sending are simpler than they are with the types of wireless apparatus now in use.

Although I have illustrated and described only a few modifications of the invention, I 120 am aware of the fact that other changes can be made therein by any person skilled in the art without departing from the scope of the invention as expressed in the claims. Therefore, I do not wish to be limited to all the 125 details herein shown and described, but

What I do claim is:—

1. In a wireless telegraph apparatus, the combination of a set of dials and indicators therefor, one at each station, means for 130

rotating said dials and indicators at each station relatively to each other, synchronously and continuously, each dial being provided with a series of characters arranged thereon in the same order, a series of contacts corresponding one with each character, circuits connected with said contacts, means for closing each circuit when the indicator of that dial indicates the character corresponding to the contact connected with that circuit, manually controlled means at one station for causing a predetermined dot and dash signal to be sent while any selected one of said circuits is closed, and wire-less apparatus connected with said circuits.

2. In a wireless telegraph or signaling apparatus, the combination of a set of dials and indicators, one at each station, means for relatively rotating the dial and indicator of each station synchronously with the rotation of those of the other station or stations, each dial being provided with a series of characters arranged thereon in the same order at the several stations and with a series of contacts corresponding with said characters, means for engaging said contacts in the same order at the several stations as the rotation is carried on, circuits connected with said contacts, a key-board at the sending station having push buttons, one connected with each of said circuits, and means connected with each push button of the key-board for closing and opening the circuit connected therewith to give a dot and dash signal.

3. In a selective signaling device, the combination of a plurality of sets of sending dials and indicators, with a set of controlling push buttons arranged in connection with each sending dial and indicator, a circuit for each dial and indicator, a plurality of branch circuits connected therewith, one for each push button, means con-

nected with the dial and indicator for closing an open contact in each branch circuit periodically, and means connected with each push button for intermittently closing and opening a second contact in each branch circuit whereby when a push button is depressed the circuit through that branch will be completely but intermittently closed during each complete operation of the device for the purpose of giving a dot and dash signal.

4. In an apparatus of the character described, the combination of a push button having a series of contacts thereon, a contact member adapted to engage said contacts in order as the push button is moved, a circuit connected with the last named contact for the purpose of giving a signal, a branch circuit, means controlled by said branch circuit for releasing the push button and permitting it to move and make the desired contact, and automatic means for operating said releasing means.

5. In an apparatus of the character described, the combination of a reciprocable rod, a push button thereon, a spring for moving the push button and rod in one direction, a latch for holding the push button and rod in one extreme position, electromagnetic means for releasing the latch to allow the spring to act, and a contact member in position to be engaged by the rod when it moves, said rod having a series of contacts thereon for engaging the contact member.

In testimony whereof I have hereunto set my hand, in the presence of two subscribing witnesses.
